UNITED STATES PATENT OFFICE

ETHAN I. DODDS, OF PULLMAN, ILLINOIS, ASSIGNOR TO THE PULLMAN COMPANY, OF CHICAGO, ILLINOIS, A CORPORATION OF ILLINOIS.

RAILWAY-CAR TRUCK.

No. 825,038.

Specification of Letters Patent.

Patented July 3, 1906.

Application filed October 30, 1905. Serial No. 285,147.

To all whom it may concern:

Be it known that I, ETHAN I. DODDS, a citizen of the United States, residing at Pullman, in the county of Cook and State of Illinois, have invented certain new and useful Improvements in Railway-Car Trucks, of which the following is a specification.

My invention pertains to the equalizing mechanism of railway-car trucks and also to the means for tying the pedestals together and involves, among other things, the use of an equalizing-bar integral with one journal-box and resting upon another box. When my invention is embodied in a six-wheel truck, the center journal-boxes each have a seat or shelf projecting from each side thereof for the equalizing-bars, which are integral with the end boxes, to rest upon. The pedestal tie-bars in this construction are flat and are fastened to the faces of the pedestals.

In the drawings which accompany this specification, Figure 1 is a side elevation of a railway-car truck embodying my invention. Fig. 2 is a partial plan view of the same, partly in section. Fig. 3 is a perspective view of one of the end journal-boxes and its integral equalizing-bar, and Fig. 4 is a perspective view of one of the center journal-boxes.

The truck comprises the usual wheel-pieces 10, to which are bolted pedestals 11, 12, and 13, in which are slidably mounted journal-boxes 14, 15, and 16, the end boxes 14 and 16 each being equipped with an integral equalizing-bar 17 and 18, respectively, the inner ends of which rest upon steps 19 of the center journal-box 15.

A description of one of the end journal-boxes will suffice for all. By referring to Fig. 3 it will be seen that the end box 14 is supplied on its sides with the usual guides 20, which coöperate with the pedestal, and it is also provided on its inner side with the integral equalizing-bar 17 mentioned above. Bar 17 has on its upper and lower surfaces integral marginal flanges 21 and 22, respectively, and on its upper surface it is also equipped with an integral spring-seat 23, having the integral circular flange 24 on its upper surface to retain the spring in place and on its lower surface with the integral bracket members 25, which connect it with the web of bar 17. At its free end the bar is supplied with a horizontal foot 26, adapted to rest

upon the adjacent step 19 of the center journal-box 15. 55

The steps 19 are integral with box 15, and each comprises a horizontal seat 27, having on its opposite sides two ribs 28, which act to prevent displacement of the ends of the equalizing-bars. The seat portion 27 is supported by integral bracket members 29, which are most clearly shown in Fig. 4. By referring to Fig. 2 it will be seen that the steps 19 and the equalizing-bars are disposed between the inner and outer plates of the pedestals, thereby forming a neat and compact construction.

It will be understood that as the load on the truck is transmitted through springs 30 to the equalizing-bars it is distributed by them upon the journal-boxes, since the bars are integral with the outer boxes and rest upon the steps 19 of the center box.

As a means to tie the pedestals together I employ a flat bar 31, which is bolted to the lower portions of the faces of the pedestals, as is shown in Fig. 1.

This patent is intended to embrace only so much of the disclosure made herein as is covered by the claims.

I claim—

1. In a railway-car truck, the combination of a journal-box having a projection on its side and an equalizing-bar resting upon said projection, substantially as described. 85

2. In a railway-car truck, the combination of a plurality of journal-boxes, one of said boxes having an integral equalizing-bar and another of said boxes having a projection on its side on which said equalizing-bar rests, substantially as described. 90

3. In a railway-car truck, the combination of a journal-box having a projection on each side and a plurality of journal-boxes, each having an integral equalizing-bar resting upon one of said projections, substantially as described. 95

4. In a railway-car truck, the combination of a journal-box having an integral projection on its side, a journal-box having an integral equalizing-bar resting upon said projection, the latter having ribs to prevent lateral displacement of said bar, substantially as described. 100

5. In a railway-car truck, the combination of a pedestal, a journal-box mounted in said pedestal and having a projection between the

inner and outer plates of said pedestal, and an equalizing-bar resting upon said projection, substantially as described.

6. In a railway-car truck, the combination of a pedestal, a journal-box mounted in said pedestal and having a projection between the inner and outer plates of said pedestal, a second pedestal, a second journal-box mounted in said second pedestal having an integral

equalizing-bar disposed between the inner and outer plates of said second pedestal, the end of said bar resting upon said projection, substantially as described.

ETHAN I. DODDS.
